UNITED STATES PATENT OFFICE.

ROSS BUXTON RATHBUN, OF SALT LAKE CITY, UTAH, ASSIGNOR TO AMERICAN SMELTING AND REFINING COMPANY, OF NEW YORK, N. Y., A CORPORATION OF NEW JERSEY.

METHOD OF CONDITIONING ELECTRODES.

Application filed June 3, 1921. Serial No. 474,798.

To all whom it may concern:

Be it known that I, Ross BUXTON RATHBUN, a citizen of the United States, and resident of Salt Lake City, in the county of 5 Salt Lake and State of Utah, have invented certain new and useful Improvements in Methods of Conditioning Electrodes, of which the following is a specification.

The invention relates in general to an improved method of conditioning electrodes in 10 the art of electrically precipitating dry solids from gases, such as the leady fumes from converters, and the invention also relates to an improved form of instrumentality for carrying out the method.

It is understood that in the practicing of this method of electric precipitation, the solid, precipitated matter especially when dry has a tendency to collect on the electrodes and as it has high dielectric strength 20 it acts to insulate the electrodes, automatically reducing the current strength to a value below what is required. Numerous attempts have been made to remedy this defect, among which might be mentioned that it has been suggested to moisten the gases carrying the particles or to moisten the precipitated particles themselves with water or acid as they come in contact with the electrodes. These methods however, use up too 30 much acid to be economical; the acid and water both act to deteriorate the apparatus, and the cooling of the gases effects the natural draft through the discharging stacks. Again it has been suggested to wet the electrodes themselves with a continuous stream 40 of water but this gives rise to a slimy precipitate which cannot be readily handled.

Accordingly, one of the objects of the invention is to provide a simple method for 45 effecting a constant, complete precipitation of the solids from the gases and in which method practically all of the solids are precipitated in a dry, readily handleable condition and, of most serious import, to provide a method which will attain these results inexpensively.

I attain this invention by intermittently treating the active faces of the electrode, 50 while not in active operation, or while in active operation, with a thin film or rather mist of a readily diffusible conducting liquid such as sulphuric acid.

So treating the electrodes has the effect

of eliminating the disadvantages in the prior methods, except possibly corrosive actions, but the use of acid of high concentration usually about 60° Bé., minimizes any acid reaction especially as the parts are protected somewhat by the dry dust coating.

It is apparently necessary for the successful operation of this method that the acid be applied uniformly over the electrode surfaces in the form of finely divided particles, and therefore one of the objects of the apparatus features of this disclosure is to provide a simple form of apparatus which will condition all of the electrodes with the same amount of acid applied in substantially the same cloud-like mist, for the wetting of any electrode with too much acid acts so as to require a lower voltage than is desirable to prevent sparking over at the electrodes.

It is sometimes more convenient to apply the cloud of acid mist to the electrodes by introducing it with the gas periodically, just before it passes through the electrodes, the mist being precipitated with the dust; but the fact that the gas or smoke is there is incidental rather than necessary, but in so far as the method feature of the disclosure is concerned the electrodes are initially treated during the period when there is no gas flow—with an atomized cloud of concentrated sulphuric acid 60-66° Bé. applied to the electrodes for a period of about a half minute or until all parts thereof are presumably covered with closely-positioned, minute drops but not so copiously applied as to cause anything in the nature of streams or a running coating of any nature. The mist is carried into contact with the electrodes by means of a current of air produced by the draft or pull of the chimney.

The gas from which the solid matter is to be precipitated is then passed through the electrostatic field formed by the energized electrodes in the manner which is well known in the practicing of the Cottrell method. The solids are precipitated from the gases; the gases pass from the electrostatic field practically clear, and this clearing of the gases will continue until the effect of the acid becomes dissipated. The flow of gas is then interrupted; all of the precipitate is possible shaken from the electrodes to enable the acid mist to contact with the electrode itself rather than the precipitated

coat of dust, the electrodes are again treated to an acid mist; the gas is again turned on and the operation repeated. A usual practice is to treat the electrodes once every twenty-four hours but this period may vary from a much shorter period to a longer one, depending on the amount of solid matter suspended in the gas, its dryness and the amount of matter present, such as lime or compounds of zinc, which have a tendency to neutralize the acid.

While the present disclosure features the spraying of the electrodes with an atomized mist of the acids, it is to be understood that this method of handling the conditioning liquids is largely to feature economy in the amount of material used and it is suggested that the acids might be otherwise applied as by painting the electrodes provided, of course, that the acids were not thickly applied or applied in any other way which might interfere with the necessary electric conditions.

Sulphuric acid has been suggested due to its relative cheapness over other suitable treating liquids; due to the fact that it is extremely divisible; due to its high boiling point; due to its high rate of diffusion over matter and due to the fact that it breaks up into three extremely mobile hydrogen radicals. It is, however, suggested that other treating materials might be used and for an illustration of one such material reference is made to nitric acid.

Referring to the apparatus features of the disclosure reference is made to the accompanying drawings of two forms of electrode treating apparatus, suitable for use in practicing the method herein featured. Figure 1 is a diagrammatic view of a screen type of treater in which the upper part is shown in plan and the lower part in elevation. Figure 2 is a similar view of a treater of the pipe type and Figures 3 and 4 are each enlarged transverse views of the distributing pipe shown in Figure 2 and taken respectively on the lines 3-3 and 4-4 of the figure.

Referring specifically to the showing in Figure 1 there are shown gas conducting conduits or flues 10 and 11, through which the gases pass horizontally and in which are hung a plurality of electrodes 12 and 13 electrically connected so as to precipitate the dust from the gas fumes passing through the flue in the manner well-known in connection with the operation of electrolytic precipitation in the screen type of treater.

The discharge electrodes which are in the form of wires, are hung from supporting pipes 14, which pipes have heretofore been in the form of conducting rods for leading the electric current to the electrodes but which, in this instance, are in the form of

pipes provided with a series of closely positioned small vents, 15, opening downwardly for the purpose of distributing the atomized acid as hereinafter more fully described. The passive or grounded electrodes, which are set in the walls transverse to the flue, are parallel to and just below the branch pipes described. They are usually screens through the meshes of which the gases pass horizontally as indicated by the arrow. These screen electrodes are shown at 12. The mist being directly downward impinges on both the wires and screens, making their surfaces conductive.

In order to meet the requirement of equal distribution and in order to reduce the time and difficulty of supplying the acid mist over the conduit, it is connected by means of a system of piping so disposed that the pressure is introduced to as large a number of points as is possible and in this way the pressure is kept fairly uniform over the entire system. For this purpose the acid inlet, 29, discharges into a main pipe, 16, of relatively large conducting capacity, which pipe, 16, branches in two ways and discharges into a plurality of distributing header pipes, 17, 18 and 19, the latter of which is positioned within the outline of a gas conduit and discharges directly into the set of spraying pipes, 14, located in the gas conduit. In so far as is possible each set of pipes collectively has a conducting capacity equal to the conducting capacity of the pipe which supplies the set so as to insure uniform velocity of the mist, thus keeping it in suspension in the several branches and preventing any of it from settling out in droplets as would be the case if the mist has too slow a velocity due to too large a pipe.

It is necessary to connect the main pipe to the supply system simply during the time when it is required to condition the electrodes and while the electric precipitating features of the device are functioning it is necessary to insulate the structure from the conditioning system. This is most readily effected by disconnecting the part of conditioning piping exteriorly of the system from the part within the gas conduit and one means for effecting this is to make a part of the piping, such as the part shown at 20, in the form of a short length of pipe connected by means of two unions which can be readily broken.

In this system it is required that air in large volume, and preferably dry, be supplied to the atomizing device and for this purpose there is disclosed an approved form of air charging conduit including, in order, a source of air under compression indicated by the supply pipe 21. This leads to a moisture trap, 22, and from the moisture trap through an air dryer, 23, from which the

dried air is discharged into an air storing receptacle, 24. From the air storing receptacle, 24, the air is discharged through a system of relatively large air supplying pipes, 25, leading to the several atomizing devices supplied from this air source.

The acid is supplied to the atomizer from an acid supply tank, 26, through a conducting pipe, 27, which leads past the control valve, 28, to a spray nozzle, 29, having a perforated head, 30, and facing in the direction of air flow through the vaporizer as is well-known in devices of this character. It is not essential that the device, 29, act as an atomizer but may serve only as a means of conveying the acid into the air stream, the atomization taking place at the small orifices.

Air pressure is maintained on the acid level in the tank, 26, from a source of air supply indicated by the pipe, 31. It is understood that the pipes 21 and 31 may be supplied from some common source of compressed air usually found in metallurgical plants.

In operation and assuming that the electrodes in the conduit, 10, and 11 are to be conditioned, the set of distributing pipes in these conduits are connected up by the insertion of the replaceable pipe connection, 20. The receiver, 24, having been filled with air to about six atmospheres, pressure, is allowed to exhaust itself through the main valve, 32, into the header system. At the same time air pressure, acting on the acid in the supply tank, forces acid therefrom through the atomizer where it is separated into extremely fine particles. The fine particles are conducted with a relatively large amount of air through the piping system, where it is divided approximately evenly and is discharged from the vents, 15, onto the electrodes as an extremely fine cloud-like mist. This cloud of mist passes through the electrodes, some of it adhering to them due to contact in passing. The remainder passes on out the main flue to the stack. When the electrodes are barely covered, as hereinbefore suggested, the supply of acid is cut off from the electrodes; the supply pipes cut off from the gas conduit, and the precipitating action is reinaugurated and continued until the gases leaving the treater begin to cloud with solids, at which time the precipitating action is stopped and the electrode re-conditioned.

It is understood that the method of applying the mist to the screen and wire electrodes is not necessarily confined to the procedure described. It may be found more convenient, for instance, to introduce the cloud of acid mist in the chamber or conduit before the gas reaches the electrodes, the mist being carried into contact with the electrodes with air or gas currents.

Referring to the disclosure in Figure 2 it will be understood that the atomizing device 29 and the parts leading thereto correspond to the similarly numbered parts in Figure 1. The atomizing device discharges into a distributing pipe 31 which extends centrally across either the top chamber or the bottom chamber 32 of a gas compartment in a well known form of pipe treater. The treater includes a plurality of pipes 33 through which the gases rise vertically. Discharge electrodes 34 are stretched axially through the pipes. The acid distributing pipe 31 is provided with a reduced extension 35 and both pipes 31 and 35 are provided with downwardly directing discharge parts 36.

The second method, used in connection with the showing in Figure 2 is essentially like that described. It is the intent in this case to pass the cloud of mist for a few moments at intervals through the pipes, conditioning their surfaces. This is accomplished by liberating the acid mist in either the top chamber or bottom chamber of gas compartment. When it is released in the upper chamber, it is necessary to do so with the gas excluded so that the mist may be carried down through the pipes by a current of air. When it is released in the bottom chamber it may be introduced in the gas column and conveyed to the electrodes by this means. It has not been found necessary to insulate the spraying apparatus in this method. Considerable advantage is obtained in having it grounded so that permanent connection may be made to the outside service.

Having thus described my invention, I claim:

1. In the art of electrical precipitation of suspended solid matter from gases, the method of maintaining a metallic electrode conductive in cases where the precipitated material is non-conducting and tends to accumulate a charge by the action of the electric field, which method consists in applying directly to the face of the electrode surface, an acid in the form of a fine mist to form on the electrode surface a thin layer capable of defeating any tendency of the charge to impair the conductivity of the metallic electrode surface.

2. In the art of precipitating suspended particles from gases by electric action, the method of maintaining conductivity between the particles and an impenetrable electrode surface which consists in confining a thin film of a conducting liquid containing sulphuric acid to the electrode surface.

3. In the art of precipitating suspended particles from gases by electric action, the method of maintaining conductivity between the particles and the active face of the electrode surface which consists in distributing

- 2 a thin film of sulphuric acid in finely divided particles over said active face.
4. In the art of precipitating suspended particles from gases by electric action, the method of maintaining conductivity between the particles and the electrode surface which consists in distributing a film of sulphuric acid in the form of a fine mist over the electrode surface.
10. 5. In the art of precipitating suspended particles from gases by electric action, the method of maintaining conductivity between the particles and the electrode surface which consists in directing onto the electrode surface and in the absence of the gases to be precipitated a fine mist of liquid constituting an electric conductor.
20. 6. In the art of precipitating suspended particles from gases by electric action, the method of maintaining conductivity between the particles and the electrode surface which consists in distributing over the electrode surface and in the absence of the gases to be precipitated, a layer of an acid distributed in finely divided particles constituting an electric conductor and capable of reducing the dielectric constant of any surface film on the particles.
30. 7. In the art of conditioning electrodes used in the precipitation of suspended solid matter from gases, the method which consists in subjecting the active surface of the electrode to a coating film of sulphuric acid deposited in the form of a fine mist.
8. In the art of conditioning electrodes used in the precipitation of suspended solid matter from gases, the method which consists in intermittently subjecting the active surface of the electrode to a coating film of sulphuric acid.
40. 9. In the art of precipitating suspended solid matter from gases by electric action, the process which consists in spraying the electrodes with sulphuric acid until the active surfaces thereof are coated with the acid, interrupting the acid spraying action, causing the precipitation of the suspended matter from the gas onto the sprayed electrodes without addition of any substance, interrupting the precipitating action as the electrodes become free of the acid coating and again spraying the electrodes with the acid.
45. 10. In the art of conditioning electrodes which consists in causing a mist of finely divided particles of sulphuric acid to adhere to an active face of the electrode and thus form a thin film on the same.
50. 11. An electrode for use in the electric precipitation of solids from gases including a metallic conductor having a thin non-flowing coating of sulphuric acid on an active face thereof.

Signed at Tacoma in the county of Pierce and State of Washington this 21st day of April, A. D. 1921.

ROSS BUXTON RATHBUN.
